UNITED STATES PATENT OFFICE

DAVID E. EVANS, OF COLUMBUS, OHIO, ASSIGNOR TO THE COLUMBUS DENTAL MANUFACTURING COMPANY, OF COLUMBUS, OHIO, A CORPORATION

DENTAL CASTING POST

Application filed May 7, 1929. Serial No. 361,022.

I am aware that casting posts have been used heretofore in dentistry, in association with artificial teeth and especially interchangeable artificial teeth. Their purpose and function are well understood by those skilled in the art.

The casting post usually is composed of a precious metal alloy. The post is so shaped and formed that only a portion engages, or 10 coacts, with an artificial tooth. The remaining portion of the casting post projects above the artificial tooth so that wax may be formed about the post to make a base, or backing member. The wax and casting post are next 15 removed simultaneously from the tooth. Then through the well-known dental casting technic the wax is replaced with metal, the latter usually composed of a stable precious metal alloy.

20 Casting posts have been made and sold by dental manufacturers to dentists, to be used in the way set forth and for the purpose of aiding in artificially restoring lost natural teeth. This method of restoration usually 25 applies to what is commonly called bridge-work.

What has been recited is understood and practiced generally in the art.

One object of my invention is to so 30 construct the casting post that it has inherent retentive, or holding power when the wax is formed about it. In the past many of the casting posts have separated from the wax during the construction of a dental bridge 35 and have thus caused loss of both labor and time. This is particularly a disadvantage to the dentist.

Another object of my invention is to so 40 construct the casting post that it has inherent retentive, or holding power, when the metal is cast against it. In the past it was not uncommon for the post to separate from the cast metal, the former sometimes pulling away bodily. This frequently occurred after 45 the bridge was in service in the patients mouth. In such cases the cast gold did not attach itself strongly to the post during the process of casting. In fact the degree of strength between the two, in repeated trials, 50 is seldom constant and poor unions are apt to

occur at any time. Such failures are serious mishaps, both to the patient and dentist. Either, or both parties suffer much inconvenience and loss of time.

Another object of my invention is to so 55 construct the casting post that it will be unnecessary to use high fusing casting metal, or over heat lower fusing casting metal in an effort to procure a rigid union between the post and casting metal. In the past it has 60 been common to over heat the lower fusing casting metals in an effort to get greater strength of union with the post by sweating or alloying. This procedure has a tendency 65 to burn out some of the lower fusing metals in the casting alloy, which may cause the alloy to change materially in its physical properties. Such physical property changes sometimes leads to failure during the casting 70 process, or may effect the tensile strength of a finished piece of work. Further, the overheating of the casting alloy often seems to have a deleterious effect upon the metal of the casting post. Breakage of the post itself, is not an uncommon failure in such instances. The exact cause of the breakage of 75 the post itself is not known to me, yet it has been construed that mixing different alloys of different characteristics may upset the physical properties of both metals. In this 80 instance the casting post is an alloy possessing different characteristics than the casting alloy. Further, it has been construed that the post breaks under these conditions because the arrangement of the molecules of the metal 85 have been disturbed and crystallization has taken place. Regardless of the exact cause, breakage of the post does occur at times when this process of high heat casting is employed. What has been said above applies in spirit 90 when a casting alloy of high fusing range is employed in association with a post whose fusing range is more or less lower.

When my casting post is employed it is 95 unnecessary to over heat the casting alloy or use a higher fusing casting alloy. Through the inherent retentive construction of my post, the casting alloy is retained in a mechanical way in addition to any surface 100

sweating union that may take place during the casting process.

Another object of my invention is to so construct the casting post that it satisfies the requirements for practical production in manufacture.

In the drawings:

Figure 1 is a side elevation of a casting post embodying my invention.

10 Figure 2 is a rear elevation of my casting post.

Figure 3 is an end elevation of the same.

The reference numeral 1 designates the post, 2 the web which is of less diameter than 15 the post, and 3 the retaining member, all formed integrally, preferably by casting. The retaining member, preferably, is wedge shape in one dimension as shown in Figure 1, the side edges 4 and 5 converging toward the 20 web 2. In the edge 9 of the retaining member 3 I provide an arcuate recess or depression and form a swelled protruded, or bulbous-like extension 10, 11 on each side wall of the retention member 3 the top of which is in the 25 plane of the bottom and side walls of the recess 8, said extensions 10, 11, functioning as additional anchorage for the backing metal cast on the post. Let it be understood that by the term post I mean the article as a whole.

30 In the manufacture of my casting post, I may choose to construct it so that the post 1 may have one or a plurality of notches 1^a as shown in Figure 1. The function of these 35 notches is to serve as a mechanical retention for the post, when the latter is assembled with the artificial tooth, the two being detachably united by cement, or any other suitable material.

It will readily be understood that the metal 40 for the backing cast to my casting post finds a very firm anchorage in the wedge formation of the retention member and in the bulbous formations 10 and 11.

What I claim is:

45 1. As a new article of manufacture, a casting post for the backing for an artificial tooth, comprising a post, a web, and a retention member having a recess in its rear edge and protuberances from two side walls 50 thereof, all formed integrally.

2. As a new article of manufacture, a casting post, for the backing for an artificial tooth, comprising a post, a web, and a retention member, having a recess in its rear edge 55 and protuberances on two side walls thereof along the bottom and side walls of the recess.

In testimony whereof I affix my signature.

DAVID E. EVANS.
